STOCKING STACKING AND BANDING
DEVICE

Edward R. Ammon, Reading, Pa.

Application September 11, 1941, Serial No. 410,485

4 Claims. (Cl. 100—31)

1

This invention is directed to a device for bundling stockings wherein stockings may be stacked in neat piles and secured by a suitable tie band. It is a particular object of the invention to provide a device of the character indicated adapted to serve as an accessory to a stocking seaming machine and in which stockings may be stacked by the machine operator as they are withdrawn from the seaming machine and banded to hold them in their stacked arrangement. Through the use of the invention the stockings reach the inspection department in neat stacks from which the stockings may be easily withdrawn by the inspector without loss of time of the inspector in preparing the stockings for examination.

According to usual practice the seaming machine operator places the stockings after seaming in loose piles of one dozen pairs, and then packs the piles into bundles which are bound with pieces of tape or other fabric strips. The bundles are delivered to the inspecting machine operator who, after untying the bundles, must straighten out the stockings and arrange them in a pile from which she can withdraw them conveniently one by one for application to the inspection machine. Considerable time is lost by the inspector in preparing the stockings as received from the seaming department for examination.

Through the use of the invention the seaming machine operator without additional effort on her part is able to arrange the stockings flat in neat piles so as to be ready for inspection without requiring additional preparation after they have reached the inspection department.

The inspection operation is carried out by placing a stocking on a form adapted to stretch the stocking at various vital points. Forms of this character are fully disclosed and described in various of my prior patents, including No. 2,010,172, granted August 6, 1935, No. 2,023,946, granted December 10, 1935, and No. 2,090,883, granted August 24, 1937. To further assist the inspecting machine operator I have in my copending application Serial No. 389,430, filed April 19, 1941, proposed to provide an adjustable tray structure in juxtaposition to the end of the inspection form in which stockings are placed when received from the inspecting department and from which the operator can draw the top end of the stocking over the inspecting form with the minimum of effort and time. To enable the full benefits of such apparatus to be obtained, it is important that the stockings be arranged preliminarily in flat piles when inserted in the tray, and this con-

2

dition is obtained in the seaming department through the use of the present invention.

The structure and advantages of the invention will be understood by reference to the illustrative embodiment thereof in the accompanying drawing and the subsequent detailed description. In such drawing:

Fig. 1 is a top plan view of my stocking seaming and banding device and illustrating its preferred position of use in association with a stocking seaming machine;

Fig. 2 is a perspective view of the device shown in Fig. 1 on a somewhat larger scale; and

Fig. 3 is a fragmentary view of a banded stack of stockings as produced through the use of the invention.

The stocking stacking and banding device is of extremely simple construction. In the embodiment shown the same takes the form of an elongated receptacle shorter than stocking length having a bottom portion 10 and opposite side walls 11 and 12. One end of the receptacle is provided with means against which the top edges of the stockings may be vertically aligned as they are stacked therein one by one. Such means preferably takes the form of a solid end wall 13. The opposite end 14 of the receptacle is open so that the lower ends of the stockings may project outwardly therethrough. A portion of the side wall 12 adjoining the open end 14 is cut away at 15 in at least its upper portion to facilitate the introduction of stockings into the receptacle. When a suitable number of stockings, say one to three dozen pairs, has been assembled in a stack 35 in the receptacle a tie band is applied to secure the stack.

To enable the stockings to be banded in the receptacle opposing portions of the side walls 11 and 12 adjacent the bottom 10 are provided with 40 openings so that a tie band may be disposed transversely of the bottom preliminary to the introduction of stockings with portions of the tie band projecting outwardly of the receptacle. Such opposing openings are extended upwardly to 45 provide guideways or slots 16 and 17 through which projecting portions of the tie band may be drawn after a stack of stockings has been assembled and secured around the sides and the top of the pile. The tie band may take the form of a piece of tape or string as indicated at 18 in Fig. 1, or if desired the tie band may comprise a circular elastic band which may preliminarily be placed in the slots 16 and 17 and extended around the end wall 13 so that after a stack of stockings 50 has been received in the receptacle the elastic

band may be stretched upwardly over the top end of end wall 13 and the adjoining portions of the side walls 11 and 12, and then allowed to contract through the upper portions of slots 16 and 17 around the top and sides of the stocking pile.

The receptacle may be formed of any suitable material such as wood or metal. Preferably the side walls 11 and 12 are lined with canvas or other suitable fabric. The purpose of such lining is not only to protect the stockings against snagging on the receptacle, but to frictionally engage the opposite sides of the stocking pile so that those stockings which have been disposed flat in the pile will not be disarranged as additional stockings are inserted into the receptacle. As shown, the fabric covering 19 may be extended over the upper edges of the side walls 11 and 12 and applied also to the exterior of such walls.

In Fig. 1 the receptacle is shown in position as an accessory to a seaming machine. Such machine 20 with its feed rolls 21 and 22 is diagrammatically illustrated in position on the usual supporting table 23. The stocking stacking and banding device is placed on table 23 with its open end projecting beyond the front edge of the table, and with its longitudinal axis at an angle of about sixty-five degrees to such table edge. The cutaway portion 15 of the side wall 12 is disposed opposite the seaming machine feed rolls 21 and 22 so that after the stocking has been fed through the rolls the operator may conveniently draw the top end of the stocking into the receptacle through the cutaway portion of the receptacle side wall. A stack 24 of stockings is shown in position in the receptacle prior to being banded by the tie band 18. As previously noted the lower portions of the stockings will project outwardly through the open receptacle end 14 and hang downwardly since it is unnecessary that the foot portions be arranged in flat form as in the case of the upper parts of the stockings.

The stack of stockings is secured by the tie band while in the receptacle by drawing projecting portions of the tie band 18 upwardly through the guide slots 16 and 17 and then securing the same. The now banded stack of stockings will then be removed from the receptacle for transportation to the inspecting department and will appear more or less as shown in Fig. 3.

Whereas under prior practices the seaming machine operator usually bundled stockings in lots of a dozen pairs, since it was difficult for her to band more than this number together when piled at random, the stockings can be conveniently piled through the use of the invention in lots of three dozen pairs. The stacks are banded in the receptacle which dispenses with the necessity of handling until after banding. The improved bundling of stockings not only saves considerable time on the part of the inspection department, but it is further found that the invention appreciably reduces handling time on the part of the seaming machine operator and enables her to obtain a greater hourly production of stockings.

What I claim is:

1. A stocking seaming machine accessory comprising a relatively narrow and elongated open-topped receptacle adapted to have stockings stocked lengthwise therein as they are removed from the seaming machine, said receptacle in-

cluding an elongated base wall sufficiently long to support the top and main leg portion of stockings but being short enough that the foot portion of stockings stacked in the receptacle will project beyond one end of the base, said base end being so formed without obstruction that the stocking foot portions will hang downwardly thereover without danger of snagging or otherwise injuring the delicate stocking fabric, opposite side wall members secured to and forming with the base wall a relatively narrow elongated stocking-receiving channel, said side walls being located in spaced apart relation just sufficient to accommodate the width of a stocking leg so that stockings received in the receptacle tend to lie flat and stack singly on top of one another in substantial vertical alignment, a vertical end wall upstanding from the base wall closing the end of the receptacle receiving the stocking tops and against which the top edges of the stockings can be stacked in substantial vertical alignment, and opposite tie band receiving narrow vertical channels in the respective sides of the receptacle above an intermediate point in the length of the receptacle base wall adapted to receive a tie band for application around the stockings stacked in the receptacle.

2. A stocking seaming machine accessory as in claim 1 wherein a portion of one of the side walls adjacent the open end of the receptacle is cut away to provide an additional open area through which the arm may be inserted in introducing stockings into the receptacle.

3. A stocking seaming machine accessory as in claim 1 further including means for frictionally engaging stockings stacked in the receptacle and holding the same against disarrangement when additional stockings are inserted in the receptacle of a character not to snag or otherwise injure the delicate stocking fabric and comprising a fabric covering lining the inner surfaces of the receptacle side walls and adapted to engage the opposite marginal areas of the stacked stockings.

4. A stocking seaming machine accessory consisting of a receptacle open at the top and at one end comprising a base member, opposite side members and one end member forming an elongated relatively narrow stocking receiving channel of just sufficient width to accommodate the width of one stocking so that through cooperation of the side and end walls stockings received in the receptacle can be stacked on top of each other in substantial vertical alignment with the top ends of the stockings against the end wall, said receptacle being of substantially greater length than width so as to accommodate therein the top and main leg portions of stockings stacked therein, but being sufficiently short that the foot portions of stockings will project outwardly through the open end of the receptacle and hang downwardly over the edge of the base member, and narrow vertical slots in the opposite sides adapted to receive a tie band for application around stockings stacked in the receptacle, said slots being located in the sides above an intermediate point of the length of the receptacle-base member nearer the closed end of the receptacle so that the tie band will engage the upper portion of the stacked stockings.

EDWARD R. AMMON.
